COMBINED CALENDAR AND REMINDER

Allan Robinson, Boston, Mass.

Application October 7, 1954, Serial No. 32,579

Term of patent 14 years

(Cl. D74—5)

Fig. 1

To all whom it may concern:

Be it known that I, Allan Robinson, a citizen of the United States and a resident of Boston, State of Massachusetts, have invented a new, original, and ornamental Design for a Combined Calendar and Reminder, of which the following is a specification, reference being had to the accompanying drawing, forming a part hereof.

The pointers in the drawing are lined for color.

I claim:

The ornamental design for a combined calendar and reminder, as shown and described.
